(57) **CLAIM**

The ornamental design for machine tool robot, as shown and described.

DESCRIPTION

FIG. 1 is a front top perspective view of machine tool robots, showing my new design;

FIG. 2 is a bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dash-dash lines indicate portions that form no part of the claimed design. The dash-dot-dash lines indicate the bounds of the claimed design beyond which no claim is made.
